CLAIM

I claim the ornamental design for a charging case, as shown and described.

DESCRIPTION

FIG. 1 is a perspective view of a charging case showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof, shown in an open position.

The broken lines shown in the drawings are for the purpose of illustrating portions of the charging case that form no part of the claimed design.

1 Claim, 8 Drawing Sheets
